(57) **CLAIM**

The ornamental design for a helmet accessory mounting system, as shown and described.

DESCRIPTION

FIG. 1 is a front perspective view of a helmet accessory mounting system showing our new design; FIG. 2 is a rear perspective view thereof; FIG. 3 is a front elevational view thereof; FIG. 4 is a rear elevational view thereof; FIG. 5 is a right-side view thereof; FIG. 6 is a left-side elevational view thereof; FIG. 7 is a top plan view thereof; and, FIG. 8 is a bottom plan view thereof.

The broken lines depicting a helmet shell and shroud represent environmental subject matter that forms no part of the claimed design. The remaining broken lines depict features of the helmet accessory mounting system that form no part thereof.

1 Claim, 8 Drawing Sheets

Related U.S. Application Data

continuation of application No. 29/752,259, filed on Sep. 25, 2020, now Pat. No. Des. 922,693, which is a continuation of application No. 29/735,709, filed on May 22, 2020, now Pat. No. Des. 900,407.
